UNITED STATES PATENT OFFICE.

WILLIAM L. VETTER, OF CHICAGO, ILLINOIS, ASSIGNOR TO SHARP & SMITH,
OF SAME PLACE.

VETERINARY MOUTH-SPECULUM.

SPECIFICATION forming part of Letters Patent No. 548,409, dated October 22, 1895.

Application filed January 21, 1893. Serial No. 459,121. (No model.)

To all whom it may concern:

Be it known that I, WILLIAM L. VETTER, a citizen of the United States, residing at Chicago, in the county of Cook and State of Illinois, have invented a new and useful Improvement in Mouth-Speculums for Horses, of which the following is a specification.

My invention relates to improvements in mouth-speculums for horses of the class employed in veterinary surgery or dentistry to hold open a horse's mouth and prevent his jaws from closing while the throat, teeth, or mouth is being operated upon.

In the drawings, Figure 1 is a perspective view of my improved speculum, showing it in its opened condition with recessed bearings to engage the teeth of a horse and with the preferred means for holding it in position upon a horse's head; Fig. 2, a broken partly-sectional view of one side of the jaw-frame, showing my improved means for locking the jaws in opened condition; and Fig. 3, a removable cross-bar for use particularly in veterinary dentistry when the front teeth of the horse are to be operated upon.

A is the frame of the speculum, having sides formed each with coincident upper jaw-pieces *t* and lower jaw-pieces *s*. The jaw-pieces *t* are curved, as shown, their convex sides being uppermost, and the lower jaw-pieces *s* are similarly curved, their convex sides being undermost. Near their rear ends the jaw-pieces *t* are curved in directions contrary to those described and are bifurcated to afford bearings *t*' *s*'. Near their bifurcated ends the jaw-pieces are formed, respectively, with side sockets *t*'' *s*''. The jaw-pieces *t* *s* fit together at their socket portions *t*'' *s*'' and are pivotally connected by means of transverse pins or rivets *r*. Pivoted upon transverse pins *t*'' in the bifurcated ends *t*' of the jaw-pieces *t* are catches *q*, serrated at their rear edges to afford engaging sockets *q*'. In the bifurcated portions of the jaw-pieces *s* are transverse pins, affording stops *s*'''. The catches *q*, which afford pivotal rack-bars, extend through the openings formed by the bifurcated ends of the jaw-pieces *s*, and above the said openings they are widened and rendered slightly concave at their rear surfaces to afford thumb-bearings *q*''.

The catches *q* afford cam-surfaces at the upper sides of the sockets *q*' and slightly recessed surfaces at the lower sides of said sockets, so that the serrated edges will move across the pins *s*'' when the jaw-pieces are spread apart and the sockets *q*' will engage the pins *s*'' under pressure exerted to close the jaws. The lower ends of the catches *q* are rounded, as shown at *q*''' and springs *q*''' fastened to the under surfaces of the jaw-pieces *t*, bear against the rounded cam-shaped ends *q*''' to press the serrated edges of the catches normally against the pins *s*'''. At their forward ends the jaw-pieces *t* are provided with flat upper surfaces *t*'' and shoulders *t*'''. On the flat surfaces *t*'' are headed studs *t*'''. The jaw-pieces *s* are provided at their forward ends with flat under surfaces *s*''', shoulders *s*''', and headed studs *s*'''.

B and B' are the upper and lower recessed teeth-engaging plates, preferably of the form shown. The plates B B' may be of exactly the same shape, and are provided in their opposite end portions with sockets *p*, just capable of receiving the shank portions of the studs *t*''' *s*'''. The ends of the plates or cross-bars B B' are rounded, as shown, and the rear sides of the said end portions present straight surfaces or end side edges *p*' to fit against the shoulders *t*''' *s*''' respectively. To place the plates or cross-bars in position they are slipped over the shank portions of the studs *s*''' *t*''' and turned until their edges *p*' engage the shoulder *t*''' *s*''' of the jaw-pieces. This manner of attaching the jaw-pieces and cross-bars together affords pivotal connections, which operate to hold the opposite sides of the speculum-frame the desired distance apart at their forward end and permit the rear portions of the said sides to be swung on the pivots afforded by the studs in the outward direction to separate them. The jaw-pieces *t* and cross-bar B form the upper jaw of the frame A, and the jaw-pieces *s* and cross-bar B' form the lower jaw of the frame. The jaws are of the same shape; but as it is desirable that the catches *q* shall in use extend in the upper direction the distinguishing terms "upper" and "lower" as applied to the jaws are employed advisedly, though the device may be used upside down. On the jaw-pieces

s is a strap α , adapted to extend under the jaw of a horse. On the jaw-pieces t is a strap y to extend over the nose of the horse, and on the pins r are pivotal eyepieces z , to which are attached a strap g' to extend over the head of the horse. The straps α y z' are the means usually employed for fastening veterinary mouth-speculums in position.

In operation the jaws of the speculum are closed to bring the cross-bars B B' together, and the said cross-bars are slipped into the horse's mouth until his upper front teeth rest in the recess of the cross-bar B and his lower front teeth in the recess of the cross-bar B' . The jaw-pieces t 's extend along opposite sides of the jaws of the animal, and the speculum is fastened in place by means of the straps α y z' . The operator then takes hold of the device at the parts adjacent to the pivots r in a manner to cause his fingers to extend around the adjacent portions of the jaw-pieces t 's and his thumbs to bear against the parts q^2 of the catches q . Pressure exerted by his thumbs against the catches releases them from the pins or stops s^3 , and the pressure of his fingers against the jaw-pieces t 's causes the latter to spread apart and open the jaws. When the mouth of the horse is opened to a sufficient extent, the operator releases the catches q^2 to cause the respective socket q' to engage the pins s^3 and hold the jaw-pieces against closing. The upwardly-curved shape of the jaw-pieces t and oppositely-curved shape of the jaw-pieces s causes them to extend above and below the sides of the horse's mouth, respectively, so that they present no obstruction. Speculums provided with straight jaw-pieces t 's are found in practice to be in the way when the back teeth of the horse are to be operated upon; but I do not limit my improvements set forth in the appended claims to use with the curved form of the jaw-pieces.

In Fig. 3 I show a cross-piece C , which may be substituted for the upper cross-piece B and lower cross-piece B' when in veterinary dentistry, for example, the upper or lower front teeth of the animal are to be left free for operation thereon. The cross-piece C is of the shape shown in Fig. 3, its ends being formed like those of the plates B B' . The bar C bears, in practice, against the gums of the animal just in rear of the front teeth, and to prevent injury to the gums each cross-bar is preferably provided with a covering of soft rubber C' . Owing to the way the cross-bars

are secured to the jaw-pieces they may be readily removed and replaced. In carrying the device about, therefore, by removing the cross-bars and closing the jaw-pieces the device may be contracted to a comparatively small compass and readily carried in the pocket.

One of the principle advantages of my improvement rests in the construction of the mechanism for locking the jaws in opened condition, wherein the locking-catches are beyond or behind the pivots r . Other constructions which have the locking mechanism at or in front of the pivots are apt to be in the way and render the operation of opening the horse's mouth, especially when the horse is vicious or resents the operation, much harder to accomplish than with my improved construction.

What I claim as new, and desire to secure by Letters Patent, is—

1. In a mouth speculum for horses, the combination of the upper and lower movable jaw-pieces pivoted together at their rear end-positions, a locking device for the jaw-pieces and mouth engaging cross-bars removably attached at their opposite ends to the forward ends of the said jaw-pieces, substantially as described.

2. In a mouth speculum for horses, the combination with the upper and lower movable jaw-pieces pivoted together at their rear end-positions, of headed studs and shoulders at the forward ends of the jaw-pieces, and cross-bars provided at opposite ends with sockets p to engage said studs and sides p' to engage said shoulders, and a locking device for the jaw-pieces substantially as and for the purpose set forth.

3. In a mouth-speculum for horses having its frame formed of sides comprising pivotally connected jaw-pieces, the oppositely curved bifurcated extensions of the jaw-pieces, behind their pivotal connections, spring-controlled rack-bars q each terminating at one end in a thumb-piece and pivoted at its opposite end to the curved rear extension of an upper jaw-piece in its bifurcated end, and a stop s^3 in the bifurcated rear extension of each lower jaw-piece and engaged by a rack-bar, substantially as and for the purpose set forth.

WILLIAM L. VETTER.
